HYDRAULIC PRESS SPEED CONTROL
MECHANISM

Francis J. Katz, now by change of name Francis J. Kent, Forest Hills, N. Y., assignor to Hydro-press, Incorporated, New York, N. Y., a corporation of Delaware

Application September 25, 1946, Serial No. 699,130

15 Claims. (Cl. 207—2)

1

This invention relates to hydraulic presses and particularly to hydraulic extrusion presses with electrically operated control means controlling the speed of operation of the press during the working stroke thereof.

In the extrusion of materials, such as high strength aluminum and magnesium alloys, it is desirable to control the extrusion so as to prevent certain defects in the extruded shapes. As an example, cracks in the extruded material constitute one of the defects that might be caused by too fast an extrusion rate, and if the extrusion speed or rate is too slow, the process may become uneconomical.

Extrusion presses have been provided with various types of manual control valves operable by the press attendant during each stroke so as to adjust the rate of supply of liquid to the hydraulic cylinder but it is apparent that such control is difficult and dependent upon the skill and knowledge of the individual attendant. The speed, for example, may change with variations in the metal, billet temperature change, and billet length.

One of the objects of this invention is to increase the operating efficiency and output of hydraulic presses and to improve the average quality of products produced thereby. This is effectuated in the present invention by providing electrical speed responsive mechanism operable in conjunction with or in coordination with the movement of the press ram or the extruded material to control hydraulic flow to the ram. The electrical quantity or voltage produced by the electrical speed responsive means is impressed upon a balancing arrangement so that when the voltage produced deviates from a predetermined value, the valve controlling fluid flow to the press will be regulated until the desired speed of the press is reached. This can be accomplished by use of a balanced relay for operating the press control valve or by providing a balancing voltage of predetermined value. In the latter case, a deviation of the speed responsive voltage from the balancing voltage will result in a potential difference which will cause current flow in a control circuit for regulation of the press control valve. By either of these means, the control thus can be arranged so that the ram will be operated at a predetermined speed during the working stroke of each cycle.

Another object of the invention is to provide a simple electrical circuit for carrying out the control and in one modification thereof to provide a circuit which can be compensated for variations

2

in the voltage used to balance the voltage produced by the speed responsive means. In one form of the invention, the correction control rate is made proportional to the magnitude of the departure of the speed from a predetermined value.

These and other objects, features, and advantages of the invention will become apparent from the following description and drawings which are merely exemplary.

10 In the drawings:

Fig. 1 is a fragmentary view partially in section of a metal extrusion press with two forms of speed regulating mechanism shown thereon for convenience, either one of which may be used 15 as described hereafter.

Fig. 2 is an enlarged fragmentary view partially in section of one form of speed regulating mechanism operated by contact with the extruded material.

20 Fig. 3 is a sectional view taken along the line 3—3 of Fig. 1, showing the control mechanism operable by means located on the ram.

Fig. 4 is a sectional view taken along the line 4—4 of Fig. 1, showing the control mechanism of 25 Fig. 2.

Fig. 5 is a diagrammatic view of a portion of the apparatus and one form of electrical circuit of the control mechanisms operated by the ram.

Fig. 6 is a diagrammatic view of a portion of 30 the apparatus and one form of electrical circuit of the control mechanism operable by contact with the extruded material.

Fig. 7 is a wiring diagram of one type of control circuit operable by either system (Fig. 5 or 35 6) to control the rate of movement of the ram.

Fig. 8 is a wiring diagram of one form of control circuit that may be used in place of the circuit of Fig. 7.

Fig. 9 is a fragmentary sectional view of one 40 type of hydraulic control valve.

Some of the principal parts of a hydraulic press are seen in Fig. 1, wherein the main hydraulic cylinder 20 has high pressure liquid or fluid of a suitable character admitted thereto through pipe 45 21, said fluid being controlled by valve 22 from supply pipe 23 which may be connected to a conventional hydraulic accumulator. Main ram 24 may have any type of plunger 25 attached thereto which is arranged to be reciprocable in billet container 26. Extrusion die 27 is held in die support 28, said die support being maintained in operating position by means of slideable wedge 29 which is vertically reciprocable by means of hydraulic mechanism 30. The die support 28 is 50 moveable to its various positions by means of hy-

draulic or similar mechanism 31. The extruded stock is illustrated at 32 after it has passed through die 27 under the urging of extrusion plunger 25. A pull-back or return ram 33 is movable by means of pull-back hydraulic cylinder 34 for the purpose of retracting the main ram.

In previous devices, the extrusion or working stroke of the ram had the speed thereof regulated by an adjustable manually operated valve in the supply line to the main hydraulic cylinder, the flow being cut down as the ram increases in speed due to decreased resistance.

In the embodiment shown herein, control valve 22 is operable by means of the multi-position main control lever 35 to govern the cycle of the press, all of the details of the valve not being shown inasmuch as they are conventional, one example of such a valve being seen in copending application Serial No. 505,110, filed October 6, 1943, now Patent Number 2,426,692. In the position shown in full lines in Fig. 1, the lever is set for admission of high pressure fluid to hydraulic cylinder 20 to produce the working stroke of the ram to force the metal in the billet container through the extrusion die. At an intermediate position 36, the valve is set for prefilling the hydraulic cylinder or moving the ram to its extruding position by a low pressure liquid at a speed many times greater than extrusion speed, this being used for the purpose of charging a billet into the billet chamber 26 in a conventional manner. A stop and a return position of the control lever are shown at 37 and 38, respectively.

In the fragmentary view of valve 22 (Fig. 9) the regulating valve portion thereof at 22' has a hydraulic fluid inlet port at 39 and an outlet port at 40, said outlet port being connected to the main hydraulic cylinder supply pipe 21. Valve 41 controls the flow of hydraulic pressure in a well-known manner, the setting of valve 41 governing the rate of supply of fluid and, therefore, the speed of the hydraulic ram. Valve 41 may be adjusted relative to its seat by changing the position of rod 42, by the action of lever 43 and adjusting screw 44, said adjusting screw being operable by large gear 45 (Figs. 1, 9), the large gear being rotatable by pinion 46 (Fig. 1) of control motor 47. It is to be understood that other types of equivalent control valves may be used, the valve itself not forming a part of the present invention.

The electrical speed responsive means is operable in conjunction or in coordination with the movement of the ram. This may be by means connected to the ram itself or by means contacting the work being extruded.

First, the control apparatus operable by means connected to the ram itself will be described. As mentioned previously, Fig. 1 for convenience shows both types of speed responsive operating means mounted on the press, only one normally being used. A track 48 (Figs. 1, 3, 5) is mounted on the cross-head 49 of ram 24 by means of brackets 50 and is movable therewith, the ram being shown in retracted position in dotted lines at 51. Tie rod 52 serves to hold platen 53 spaced relative to flange 54 of hydraulic cylinder 20 and rod 52 can carry the ram operated control mechanism shown generally at 55. The control mechanism comprises a roller 56 connected to a conventional tachometer generator 57 in some suitable manner such as by belt 61. The roller 56 is supported on oscillatable arm 58, said arm being pivoted at 59 to the frame 60. A belt or driving means 61 is used to connect the roller 56

56 to the tachometer generator 57. A spring 62 holds the roller in a normally elevated position or a position wherein it will not contact track 48 as track 48 is moved under roller 56.

5 A switch 63 operable by lever 35 (Figs. 1 and 5), may be provided so as to complete the circuit to solenoid 64 when the operating lever is in position for the extrusion stroke of the ram. Solenoid 64 is connected to arm 58 by a link 64'. In 10 Fig. 5, operating lever 35 is shown in the extrusion stroke position and when in this position, switch 63 is closed so that current will flow from power lead 64, switch 63, wire 69, magnetic switch coil 65, to push button 66. At the start of the 15 extrusion stroke, push button 66 is depressed which will complete the circuit to magnetic switch 66' and cause blades 67 and 68 thereof to close, thereby completing the circuit from switch 63, wire 69, switch blade 68, wire 70, solenoid 64, wire 71 back to power lead 72, thereby providing the holding circuit for the magnetic switch solenoid 65. Energization of solenoid 64 will cause clockwise rotation of lever 58 (Fig. 5), thereby bringing roller 56 into contact with track 48 20 which will cause rotation of roller 56 and operation of the tachometer generator 57. A speed indicating voltmeter 176 may be connected to leads 75. The voltage generated in leads 75 may be employed in the manner hereafter described to 25 operate the control motor 47 of hydraulic regulating valve 22 so that the hydraulic fluid will be supplied to the hydraulic cylinder 20 in accordance with the speed of the ram.

30 A control voltage related to the speed of the extrusion press also may be obtained from the movement of the extruded metal itself as will now be described. A roller 76 (Figs. 1, 4, and 6) is carried by frame 77, said frame being pivoted on rod 78 to platen 53. Tachometer generator 40 79 is mounted on frame 77 and is driven by belt 80, said belt in turn being driven by roller 76. The roller 76 and frame 77 are raised and lowered so that the roller can come in contact with the material being extruded. One way in which the lowering and raising can be accomplished is by attaching a cable 80 to the wedge raising hydraulic cylinder cross-head 81, said cable passing over a pulley 82. When the wedge 29 (Fig. 6) is in its upper or non-extruding position, the roller 76 is raised up above the extrusion bed. When the wedge is placed in its lower position (broken lines, Fig. 6) so as to hold the extrusion die in place, cable 80 will take the broken line position 80' of Fig. 6 and the roller lowered so that it can make contact with the stock 83 as it is extruded. In this manner, the speed of extrusion of the stock is used to produce a voltage or electrical quantity at leads 84, which is proportional or related to the speed of said extrusion, voltmeter 85 being provided similar to voltmeter 176 of Fig. 5. In this case it is not necessary to have a limit switch as for the device of Fig. 5, inasmuch as there is no operation of the roller 76 and tachometer until the stock actually contacts the same.

65 Either of the control voltages or electrical quantities produced by the tachometers of Fig. 5 or 6, may be employed to operate the circuit of Fig. 7 or 8 so as to change the adjustment of the hydraulic fluid control valve and thereby adjust the speed of operation of the main ram or speed of the extrusion of the metal so as to maintain said speed at a predetermined value.

70 Referring to Fig. 7, the control voltage produced 75 by the system of either Fig. 5 or Fig. 6 may be

connected by leads 86 to the solenoid 87 of the floating voltage relay 88. Switch contact lever 89 is pivoted at its center and has contacts 90 and 91 mounted thereon, there being spring 92 connected thereto in a conventional manner. Armature 93 is affixed to lever 89 and is operable by solenoid 87. Reversing switch 94 has solenoids 95 and 96 for operating two sets of contacts 97 and 98, respectively. At a given voltage or speed of the tachometer, switch lever 89 will be maintained in a position where neither contact 90 nor 91 is operable.

If, for example, the speed changes from a predetermined value in a direction such as to cause contact 90 to be raised, magnet coil 95 will be energized from power lead 99, through wire 100, solenoid 95, contact 90, wire 101, to power lead 102. This will cause the set of contacts 97 to close and connect leads 103 and 104 with leads 105 and 106, respectively, to cause the control motor 107 to rotate in a predetermined direction and thereby change the setting of regulating valve 22.

The resistance 86' may be adjustable so as to permit adjustment of current in solenoid 87 so as to select the control speed.

In the event the control voltage fed to the leads 86 moves in the opposite direction to that just mentioned, contact 91 will be raised and 90 will be lowered so that solenoid 96 will be operated to close the set of contacts 98. This will connect leads 103 and 104 to 106 and 105 and thereby the power leads 99 and 102 in a different direction than when contact 90 is closed to energize solenoid 95. There will thus be a control of motor 107 in a direction depending upon whether contact 90 or 91 is closed.

After the speed of the ram or extruded metal has reached the predetermined value, switch arm 89 will take the neutral position shown in Fig. 7 and thereby stop the regulating motor.

A second form of control device for the regulating motor is shown in Fig. 8 wherein three generators of suitable types are indicated at 108, 109, and 110, these generators being driven by a constant speed motor 111 through the shaft diagrammatically indicated at 130. The tachometer is shown at 112 and this may be the tachometer 57 or 79 of Fig. 5 or 6. The regulating valve motor is shown at 113 and a speed indicating voltmeter at 114. The voltage generated by tachometer 112 is balanced by the voltage of generator 110, tachometer 112 being connected to wire 115, field 116 of generator 108, wire 117, generator 110, and wire 118. The resulting current flow therethrough, if there is a potential difference existent, will furnish the excitation for field 116 of generator 108, generator 108 being connected through leads 119 and 120 to the armature of the valve regulating motor 113.

Generator 109 is employed to furnish excitation for the field 121 of the tachometer 112 and the field 122 of the valve operating motor 113. Generator 109 is connected through bus 123 to field 121 and field 122, respectively. In this arrangement, the speed of the press or device controlled may be chosen by setting of variable resistance 126 in the field 127 of generator 110 which will change the no-flow current condition through field 116. The system will be in equilibrium when the tachometer generator voltage is balanced by the voltage of generator 110. The excitation for the valve operating motor and tachometer can be adjusted by means of resistance 128 in the field winding 129 of generator 109. It is evident that in this arrangement, the reg-

ulating action of valve operating motor 113 will be governed both in direction and in proportion to the magnitude of deviation of the extrusion speed from a predetermined value. In other words, the higher the speed above or below a predetermined value, the faster will the valve regulating motor be operated to a new setting because the field in 116 will be stronger with a greater departure.

The control system described herein is especially adapted for hydraulic presses used for different purposes wherein it is desired that the operation of the press take place at a constant rate of speed and provides a simple electrical circuit for accurately maintaining the speed of the ram at said predetermined value.

It is apparent that variations may be made in the forms of the device shown without departing from the spirit of the invention as defined in the appended claims.

20. What is claimed:

1. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, regulatable fluid supply means for said cylinder, electric voltage producing speed responsive means operable in coordination with the movement of said ram, and means connected to said regulatable fluid supply means and with said speed responsive means operable in accordance with the voltage of said speed responsive means to regulate said fluid supply system whereby the movement of said ram relative to said forming means is maintained constant during each working stroke thereof.

2. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, regulatable fluid supply means for said cylinder, electric voltage producing speed responsive means operable in coordination with the movement of said ram, and means connected to said regulatable fluid supply means and with said speed responsive means operable when said voltage varies from a predetermined value to regulate said fluid supply system whereby the movement of said ram relative to said forming means is maintained constant during each working stroke thereof.

3. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, regulatable fluid supply means for said cylinder, electric voltage producing speed responsive means operatively connected to said ram, and means connected with said regulatable fluid supply means operable when said voltage varies from a predetermined value to regulate said fluid supply system whereby the movement of said ram relative to said forming means is maintained constant during each working stroke thereof.

4. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operated by move-

ment of material acted upon by said ram, and means connected with said fluid supply means and the speed responsive means operable when said voltage varies from a predetermined value to regulate said fluid supply system whereby the movement of said ram relative to said forming means is maintained constant during each working stroke thereof.

5. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, regulatable fluid supply means connected to said cylinder, electric voltage producing speed responsive means operable in coordination with the movement of said ram, balancing means connected to said fluid supply means to regulate said fluid supply system, said balancing means being connected with said speed responsive means and energizable when said voltage produced by said speed responsive means deviates from a predetermined standard, whereby movement of said ram relative to said forming means is maintained constant during each working stroke thereof.

6. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operable in coordination with the movement of said ram, a floating relay operable by said speed responsive means, and means connected with said fluid supply means controlled by said relay and operated when said voltage varies from a predetermined value to regulate said fluid supply means whereby the movement of said ram relative to said forming means is maintained constant during each working stroke thereof.

7. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operable in coordination with the movement of said ram, a voltage source of predetermined value connected to said speed responsive means for balancing said speed responsive means voltage when said responsive means is operated at a predetermined speed, and means connected with said fluid supply means and controlled by the resultant current when the speed deviates from a predetermined value to regulate said fluid supply system whereby the movement of said ram relative to said forming means is maintained constant during each working stroke thereof.

8. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operable in coordination with the movement of said ram, a motor operated regulating valve for said fluid supply means, a generator connected to said fluid supply means, a generator connected to said regulating valve motor, means connecting

said speed responsive means to a source of predetermined voltage through the field of said generator, whereby when the voltage produced by said speed responsive means deviates from a predetermined value, a current will flow through said field to operate said regulating valve to regulate the fluid supply to maintain movement of said ram relative to said forming means constant during each working stroke thereof.

10. 9. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operably connected to said ram, a floating relay operable by said speed responsive means, and means controlled by said relay and operated when said voltage varies from a predetermined value to regulate said fluid supply means whereby the movement of said ram relative to said forming means is maintained constant during each working stroke thereof.

15. 10. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operable by said ram, a voltage source of predetermined value connected to said speed responsive means for balancing said speed responsive means voltage when said responsive means is operated at a predetermined speed, and means connected with said fluid supply means controlled by the resultant current when the speed deviates from a predetermined value to regulate said fluid supply system whereby the movement of said ram relative to said forming means is maintained constant during each working stroke thereof.

11. 11. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operatively connectable with material acted upon by said ram and operable by movement of said material, a voltage source of predetermined value connected to said speed responsive means for balancing said speed responsive means voltage when said responsive means is operated at a predetermined speed, and means controlled by the resultant current when the speed deviates from a predetermined value to regulate said fluid supply system whereby the movement of said ram relative to said forming means is maintained constant during each working stroke thereof.

12. 12. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operable by movement of material acted upon by said ram, a motor operated regulator for said fluid supply means, a generator connected to said regulating valve motor, and means connecting said speed re-

sponsive means to a source of predetermined voltage through the field of said generator whereby when the voltage produced by said speed responsive means deviates from a predetermined value, a current will flow through said field to operate said regulating valve and regulate the fluid supply and thereby maintain movement of said ram relative to said forming means constant during each working stroke thereof.

13. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means for said cylinder, electric voltage producing speed responsive means operable in coordination with the movement of said ram, a motor controlled fluid supply valve, and means connected to said motor control valve to operate the same in a direction and at a rate in proportion to the magnitude of the departure of the voltage produced by said electric voltage producing speed responsive means from a predetermined value.

14. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means connected to said cylinder, a regulatable fluid supply control means in said supply means, electric voltage producing speed responsive means, a connection between said speed responsive means and said ram to drive said speed responsive means and produce a voltage, and means connected to said fluid supply control means and said speed responsive means operating said control means when the voltage produced by the speed responsive means varies from a predetermined value to regulate the fluid supply

system so as to maintain the ram speed constant during each working stroke thereof.

15. In a hydraulic press, the combination including a frame, a hydraulic cylinder on said frame, a ram reciprocable in said cylinder and movable through a working stroke by hydraulic pressure in said cylinder, work forming means on said frame and operated upon by said ram, fluid supply means connected to said cylinder, a regulatable fluid supply control means in said supply means, electric voltage producing speed responsive means, a connection between said speed responsive means and said ram to drive said speed responsive means and produce a voltage, said connection being movable to operative position during the working stroke of the ram, and means connected to said fluid supply control means and said speed responsive means operating said control means when the voltage produced by the speed responsive means varies from a predetermined value to regulate the fluid supply system so as to maintain the ram speed constant during each working stroke thereof.
